CLAIM

We claim the ornamental design for a combined thermal bottle and cups, as shown and described.

DESCRIPTION

FIG. 1 is a front view of a combined thermal bottle and cups, the undisclosed opposite side being a mirror image;

FIG. 2 is a right side view thereof;

FIG. 3 is a left side view thereof;

FIG. 4 is a top view thereof;

FIG. 5 is a bottom view thereof;

FIG. 6 is a front view thereof, the undisclosed opposite side being a mirror image, shown without the cups for clarity of illustration;

FIG. 7 is a right side view of FIG. 6 thereof;

FIG. 8 is a left side view of FIG. 6 thereof;

FIG. 9 is a top view of FIG. 6 thereof;

FIG. 10 is a perspective view of FIG. 6 thereof;
FIG. 11 is a front view of one of the cups, the undisclosed
opposite side being a mirror image;
FIG. 12 is a top view of FIG. 11;
FIG. 13 is a bottom view of FIG. 11;

FIG. 14 is a right side view of FIG. 11;
FIG. 15 is a left side view of FIG. 11; and,
FIG. 16 is a perspective view of FIG. 11.
